CLOSURE MEANS FOR CONTAINERS

Filed July 2, 1951

UNITED STATES PATENT OFFICE

2,670,097

CLOSURE MEANS FOR CONTAINERS

George Strickland, St. Catherines, Ontario, Canada, assignor to American Flange & Manufacturing Co. Inc., New York, N. Y., a corporation of Delaware

Application July 2, 1951, Serial No. 234,747

5 Claims. (Cl. 220—40)

1

This invention relates to improvements in a closure means for containers, as described in the present specification and illustrated in the accompanying drawings that form a part of the same.

The invention consists essentially in the novel features of construction as pointed out broadly and specifically in the claims for novelty following a description containing an explanation in detail of an acceptable form of the invention.

The objects of the invention are to devise a closure means which may be readily and easily removed from the container which could be in the form of a metal drum, a can, a jar, a bottle, or similar articles; to contrive a closure means for containers which will be easy to manufacture and consequently lessen the cost of production; to furnish a closure and cover which will be sturdy and form a strong unit and with which no special tool is needed for its removal; to make a closure means for containers forming a perfect seal, and which will be locked to the container; and generally to provide a closure and cover for containers of neat and attractive appearance and which will be efficient in use.

In the drawings:

Figure 1 is a side elevation showing a container with the closure and cover in position thereon.

Figure 2 is an enlarged plan view of Figure 1.

Figure 3 is an enlarged fragmentary side view, showing the closure and cover in position on top of the container.

Fig. 3a is an enlarged vertical section of the lock-bracket for the cover.

Figure 4 is an enlarged plan view, showing the closure in position on the container with the outer locking cover removed.

Figure 4a is an enlarged fragmentary view of the gasketing of the closure with respect to the container opening.

Figure 5 is an enlarged fragmentary side sectional view through the closure and top portion of the container, as taken on the line 5—5 in Figure 4.

Figure 6 is an enlarged fragmentary side sectional view through the top portion of the container, with the closure and cover removed therefrom.

Like numerals of reference indicate corresponding parts in the various figures.

Referring to the drawings, the closure means, as indicated by the numeral 10, consists of a closure 11 having an outer cover 12 sealing the same in position on the top of a container 13.

The container 13 in this instance is shown in

2

the form of a can, the top 14 of which has an opening 15 with a plurality of formations there-around to coincide with the formation of the closure 11 so as to effect a sealing when both are brought into engagement with one another.

The opening 15 is centrally located and has its annular edge extending downward and inward at an angle from the top of the container for a suitable distance, then continuing vertically downward a short distance and then inwardly horizontally to form an annular shelf or seat 16 for a gasket, this seat extending towards the center of the opening.

The remaining portions or formations of the opening 15 extending downward from the seat 16, consist of a plurality of flange portions 17 extending downwardly and inwardly at an angle, then vertically for a suitable distance, and the lower edges thereof are turned outwardly at right angles to the latter. Slots 18 are formed between each of the flange portions 17, and the lower edge 18 of each portion is in the form of a cam, in that the edge tapers downward in a horizontally inclined plane from one of the slots 18 for a suitable distance, and then extends horizontally and terminates in a projection 20 adjacent the next slot. Each of the lower edges 18 extends in a similar manner to the foregoing between each of the slots.

The opening 15 in the top of the container 13 is illustrated, in this instance, as being formed directly in the container stock, but it will be realized that, if necessary, a flange could be attached to the top of the container and have this opening 15 formed therein.

The closure 11 is adapted to engage in the opening 15 in the top of the container for the purpose of closing or sealing the same. The closure consists of a stopple portion 21 having tightening means welded or otherwise secured to the bottom thereof. The tightening means 22 consists of a body portion 23 which is in the form of a cap having a flat top surface and an annular skirt extending downward therefrom. A plurality of lugs 24 are integral with the body portion 23 and extend downward at right angles from the lower edge of the annular skirt thereof.

The stopple portion 21 has a flat bottom portion 25 which is adjacent the flat upper portion 50 or surface of the body portion 23 of the tightening means 22, and an annular and arcuately shaped side wall 26 extends upward and outward from this bottom portion 25.

An annular lip 27 extends around the upper edge of the side wall 26 and has a plurality of

slots 28 therein. The lip 27 is preferably formed by curling the material of the side wall 26 outwardly to form a rolled edge. The annular seat 16 formed in the opening 15 of the container 13 has a gasket 29 positioned thereto. When the closure 11 is placed in the opening 15 in the top of the container, the closure is turned so that the lugs 24 on the tightening means thereof extend through the slots 19 in the opening 15, and the closure is then turned and the lugs 24 engage the lower edges or cams 18 of the flange portions 17, thus tightening down the closure with respect to the opening 15 and securing the same thereto.

The slots 28 in the annular lip 27 of the closure are adapted to be engaged by any suitable means for turning the closure. The lower edges 18 of the flange portions 17 extend slightly downward along a portion thereof, and then these edges extend horizontally until they meet the projection 20 on each of these flange portions 17, which serve as a stop for the lugs 24 when the closure 11 has been turned to become secured in the opening 15.

When the closure 11 is substantially secured in the opening 15, the annular and arcuately shaped side wall 28 of the stopple portion 21 engages the gasket 29 on the seat 16, thereby substantially sealing the opening.

After the closure 11 is in place on the container 13, the outer cover 12 is applied over the top of the closure and is clinched over the rolled edge or annular lip 27 to substantially grip the same. A tongue 30 is integral with the outer cover 12 and extends outward from one side of the cover at the bottom thereof. A lock bracket 31 is fixedly secured to the top 14 of the container 13 towards the periphery thereof, and the end of the tongue 30 is substantially engaged in a slot 32 therein, thus locking the outer cover 12 in position with respect to the container.

In removing the outer cover 12, prior to removing the closure from the container, the tongue 30 is broken so that it may be gripped and torn across the central portion of the outer cover, thereby freeing the same from the closure. This outer cover 12 provides a finished surface with the closure as well as a locking means therefor, and may be suitably lithographed if desired.

It is of course understood that modifications and ramifications may be made without in any way departing from the spirit of the invention as hereinabove described and illustrated.

What I claim is:

1. In a closure means for containers, a container having an opening in the top thereof formed of a plurality of annular formations extending downward and inward from the top thereof, a gasket suitably seated with respect to said annular formations, cams being formed on the lowermost of said annular formations, a closure comprising a stopple portion and tightening means, said stopple portion having a flat bottom wall and an arcuately shaped annular wall extending upward therefrom the top edge of which is provided with a plurality of slots extending therethrough, said tightening means comprising a flat wall fixedly secured to the flat bottom wall of said stopple portion and an annular skirt extending downward from said top wall of said tightening means, a plurality of lugs extending downward from the lower edge of said annular skirt of said tightening means, said closure being positioned in the annular formations forming the hole in the top of said container for closing the same and the arcuately shaped annu-

lar wall of said stopple portion being seated on said gasket and being tightened down thereagainst as said lugs on said tightening means thereof engage with said cams in said container when turned to a tight position.

2. In a closure means for containers, a container having an opening in the top thereof formed of a plurality of annular formations extending downward and inward from the top thereof, a gasket suitably seated with respect to said annular formations, cams being formed on the lowermost of said annular formations, a closure comprising a stopple portion and tightening means secured on the bottom thereof, said stopple portion having a flat bottom wall and an arcuately shaped annular side wall extending upward and outward therefrom, the top edge of the side wall being rolled, forming a lip portion, said rolled edge having a plurality of slots extending therethrough, said tightening means comprising a flat wall fixedly secured to the flat bottom wall of said stopple portion and an annular skirt extending downward from said top wall of said tightening means, a plurality of lugs extending downward from the lower edges of said annular skirt of said tightening means, said closure being positioned in the annular formations forming the hole in the top of said container for closing the same and the arcuately shaped annular wall of said stopple portion being seated on said gasket and being tightened down thereagainst as said lugs on said tightening means thereof engage with said cams in said container when turned to a tight position, an outer cover adapted to be positioned over said closure and clinched over said rolled edge thereof, a tongue integral with said outer cover and extending outward from one side thereof, a lock bracket fixedly secured in the top of said container towards the periphery thereof and adapted to have the end of said tongue substantially engaged therewith, thus locking said outer cover in position with respect to said container, and said tongue facilitating the removal of said outer cover from said closure by rendering the same easy to break so that it may be drawn across the central portion of said outer cover thus separating said outer cover into sections for removal from said closure.

3. In closure constructions for containers, a container wall formed with an opening therein, said opening being bordered by a downwardly extending annular formation, said annular formation terminating at its inner end in cam-like formations and a closure for closing said opening, said closure comprising a pair of opposed cup-like elements, said cup-like elements being assembled with the outer surfaces of their bottoms secured together in face-to-face relationship, the upper one of said cup-like elements being seated within said annular formation to close said opening, a gasket received between the outer wall of said one cup-like element and said annular formation and engaged by each to provide a leak-proof joint, the lower of said cup-like elements having a portion extending through said opening, said extending portion providing cam engaging portions formed to engage said cams at the inner end of said annular formation, said cam engaging portions engaging said cams and said cams being inclined whereby on the turning of said closure with said cam engaging portions and said cams in engagement, said outer cup-like element will be drawn into formation with said gasket to provide a tight closure.

4. In closure constructions for containers, a

container wall having an opening therein, said opening being formed with a downwardly extending annular formation bordering the same, a gasket seat formed in said annular formation, cams formed on said annular formation at the lower end thereof, and a closure for closing said opening, said closure comprising a pair of opposed cup-like elements, said cup-like elements having the outer surfaces of their bottoms secured together in face-to-face relationship, the upper one of said cup-like elements being seated within said annular formation to close said opening, a gasket carried by said gasket seat on said annular formation and engaging the outer wall of said upper cup-like element, the lower of said cup-like elements having a portion extending through said opening and terminating in outwardly extending cam-engaging portions, said outwardly extending cam engaging portions engaging said cams and said cams, on the turning of said closure, serving to draw said outer cup-like element down into said formation against said gasket to provide a tight closure.

5. A closure plug for containers which comprises, a pair of cup-shaped elements comprising a closing element and a securing element, said elements being assembled and secured to-

10

25

gether in opposed relation with the outer bottom surfaces thereof in face-to-face engagement, said closing element being formed as a convexly extending dome extending away from the bottom surface thereof and terminating in a reinforcing edge, said reinforcing edge being provided with wrench engaging formations, said securing element having a side wall extending away from the bottom surface thereof and said side wall terminating in an outwardly extending edge, said outwardly extending edge being formed as spaced cam formations.

GEORGE STRICKLAND.
